(57) **CLAIM**

The ornamental design for a “hand cleaning foam sponge,” as shown and described.

DESCRIPTION

FIG. 1 is a front top right perspective view of a “hand cleaning foam sponge” showing our new design;

FIG. 2 is a front elevational view thereof;

FIG. 3 is a top plan view thereof;

FIG. 4 is a left side elevational view thereof, the right side being identical thereto, and,

FIG. 5 is a bottom plan view thereof.
